UNITED STATES PATENT OFFICE.

LUTHER MCNAIR, OF BROOKLYN, NEW YORK.

SANITARY ATTACHMENT FOR DRINKING-GLASSES.

1,034,636.

Specification of Letters Patent.

Patented Aug. 6, 1912.

Application filed March 13, 1912. Serial No. 683,482.

To all whom it may concern:

Be it known that I, LUTHER MCNAIR, a citizen of the United States, and residing at Brooklyn, in the county of Kings and State 5 of New York, have invented certain new and useful Improvements in Sanitary Attachments for Drinking-Glasses, of which the following is a specification, such as will enable those skilled in the art to which it 10 appertains to make and use the same.

This invention relates to sanitary attachments for drinking glasses, cups, goblets and the like, and the object thereof is to provide an improved device of this class, 15 which may be easily attached to, and detached from an article of the class specified, whenever desired, and which is intended to prevent the lips or any part of the mouth 20 from coming in contact with the glass, cup or goblet in the operation of drinking.

The invention is fully disclosed in the following specification of which the accompanying drawing forms a part in which the 25 separate parts of my improvement are designated by suitable reference characters in each of the views, and in which:

Figure 1 is an inside or front view of my improved attachment;—Fig. 2 a back view of the attachment showing the same connected with an ordinary glass or goblet. Fig. 3 a section on the line 3—3 of Fig. 2. Fig. 4 a section on the line 4—4 of Fig. 2, and;—Fig. 5 a view similar to Fig. 3, but showing a modification.

My improved drinking glass attachment *a* involves a frame composed of spring wire, or a spring rod or of any other suitable material, and comprises an inner or front yoke-shaped member *b* which opens upwardly, 30 and an outer or back yoke-shaped member *c* which opens upwardly, and the sides of which are divergent and connected at the top as shown at *d* to form side loops *e* which open downwardly.

The side parts of the outer or back yoke-shaped members *c* are connected by a transverse plate *f*, the ends of which are preferably folded around said side part as shown at *f*², but this connection may be made in 40 any desired manner, and connected with the top edge of the transverse top plate *f* is a flexible sheet *g* of rubber, or other suitable material which is carried down to the bottom of the front yoke-shaped member *b*, and secured thereto as shown at *g*², this connection being preferably made by a tubular

clamp as shown, and in practice the back transverse plate *f* is preferably made of two thicknesses, and the sheet *g* is secured between said thicknesses as shown.

In the form of construction shown in Figs. 1 to 4 a downwardly directed spring tongue *h* is secured to and centrally of the bottom of the back yoke-shaped member *b* of the device, and this spring tongue *h* aids 60 in holding the attachment in position when in use. The side yoke-shaped members *e* which open downwardly are provided at the top thereof, and on the inner sides thereof with transverse flexible sheets *i*, similar to 65 the sheet *g*, which are secured thereto in any desired manner, and which extend downwardly to the top edge of the transverse plate *f*, and to the top fold of the sheet *g*, and in the use of this device it is connected 70 with a glass, cup or similar article *j* as shown in Figs. 2, 3¹ and 4, the top edge of the glass or cup, at one side thereof, being passed upwardly into the device or 75 between the side loop or yoke-shaped members *e* in such manner that the sheet *g* will be on the inner side of the glass or cup, and the plate *f* on the outer side thereof in which 80 position of said parts the tongue *h* will bear on the back or outside of the glass or cup, and hold the attachment in position, and in 85 the operation of drinking the transverse plate *f* will come in contact with the bottom lip, and the sheet *g* with the upper lip, and the yoke-shaped side members *e*, at the top 90 thereof, and the sheets *i* secured thereto will guard the sides of the mouth or the ends of the lips, and prevent the same from coming in contact with the glass.

The construction shown in Fig. 5 is the 95 same as that shown in Figs. 1 to 4 inclusive, except that the spring tongue *h* is omitted, and in practice the device may be made sufficiently elastic to hold it in position on the glass or goblet without the use of the spring 100 tongue *h*.

In the construction shown in Figs. 1 to 4, the bottom of the yoke-shaped member *b* is divided centrally, and provided with angle members *k*, which extend upwardly, but in 105 the construction shown in Fig. 5 these angle members *k* extend downwardly and bear on the outer side of the glass or goblet, but this construction, also, is immaterial, as the frame of the device may be made sufficiently 110 elastic to hold it in position.

It will be understood that this attachment

may be carried by the owner or user in any way, and may be applied whenever desired, and may be cleaned whenever necessary; my invention is not limited to the particular construction herein described, nor to any particular material employed, and changes in and modifications of the form and construction of the device, as herein described, may be made, within the scope of the appended claims without departing from the spirit of my invention or sacrificing its advantages.

Having fully described my invention what I claim as new and desire to secure by Letters Patent, is:—

1. A sanitary attachment for drinking glasses, goblets and the like, said attachment comprising a frame composed of front and back yoke-shaped members which open upwardly, and the sides of which are connected to form side yoke-shaped members which open downwardly, the back yoke-shaped member being provided with a transverse plate and a flexible sheet connected
- 20

with the top of said plate, and with the bottom of the front yoke-shaped member.

2. A sanitary attachment for drinking glasses, goblets and the like, said attachment comprising a frame composed of front and back yoke-shaped members which open upwardly, and the sides of which are connected to form side yoke-shaped members which open downwardly, the back yoke-shaped member being provided with a transverse plate and a flexible sheet connected with the top of said plate, and with the bottom of the front yoke-shaped member, and the tops of the side yoke-shaped members which open downwardly being also provided with transverse sheets.
- 30

In testimony that I claim the foregoing as my invention I have signed my name in presence of the subscribing witnesses this 11th day of March 1912.

LUTHER McNAIR.
